(57) **CLAIM**

The ornamental design for a beverage container cap, as shown and described.

DESCRIPTION

FIG. 1 is an isometric view of a beverage container cap showing the new design.

FIG. 2 is a first side elevation view of the cap of FIG. 1. FIG. 3 is a second side elevation view of the cap of FIG. 1 taken from the side that is opposite the side shown in FIG. 2.

FIG. 4 is a third side elevation view of the cap of FIG. 1 taken from a side rotationally between the sides shown in FIGS. 2 and 3.

FIG. 5 is a fourth side elevation view of the cap of FIG. 1 taken from the side that is opposite the side shown in FIG. 4.

FIG. 6 is a top plan view of the cap of FIG. 1.

FIG. 7 is a bottom plan view of the cap of FIG. 1; and, FIG. 8 is an isometric environment view of the cap of FIG. 1 on a beverage container.

The broken lines shown in FIGS. 1-7 depict portions of the beverage container cap that form no part of the claimed design. In FIG. 7, all areas within the solid line perimeter are not claimed. The broken lines in FIG. 8 depict environment that forms no part of the claimed design. The shading lines shown in the drawings represent the approximate three-dimensional contour of the claimed design and are not intended to indicate surface decoration.
